UNITED STATES PATENT OFFICE.

DAVID ALLEN METZ, OF PHILADELPHIA, PENNSYLVANIA.

ELECTROPLATING APPARATUS.

1,315,029.

Specification of Letters Patent.

Patented Sept. 2, 1919.

Application filed September 21, 1918. Serial No. 255,020.

To all whom it may concern:

Be it known that I, DAVID ALLEN METZ, a citizen of the United States, residing in the city and county of Philadelphia, State of Pennsylvania, have invented a new and useful Electroplating Apparatus, of which the following is a specification.

My invention relates in general to solution-stirring apparatus applicable to electrolytic tanks for refining metals by producing agitation and electro-deposition, and relates more particularly to and comprehends a novel means for effecting the agitation of the electrolyte which can as a unitary structure be applied to tanks of different dimensions and construction.

It is well known that a controlled and active circulation of the electrolyte in the refining or plating tank is a desirable feature as tending to produce smooth and even deposition upon the cathode, and my invention comprehends an organized unitary mechanical apparatus for agitating or stirring the solution in a simple, cheap and effective manner in any type of tank provided with the necessary anodes and having the usual electrical connections.

My invention having general reference, therefore, to improvements in apparatus used for producing the electro-deposition of metals, it embraces more particularly a novel organization of assembled means for agitating the articles to be plated within the plating solution, and its object is to provide such a means as can as a whole be applied to various tanks and as so applied insure that the plating process can be carried out efficiently and in a very short time.

With the foregoing objects in view, my invention comprehends a certain novel unitary organization of agitating devices for electro-plating tanks and of the driving mechanism therefor, and, further, a novel arrangement and combination of said devices and their adjunctive parts, as well as the details of the construction of the same, all as hereinafter fully described.

For the purpose of illustrating my invention, I have shown in the accompanying drawings a certain type and embodiment of it which is at present preferred by me, because in practice it has given satisfactory and reliable results.

It is to be understood, however, that the various components in which my invention is shown as embodied can be variously ar-

ranged and organized and that my invention is not therefore to be closely limited to the precise arrangement and organization of the components typified in the construction depicted in the accompanying drawings and herein described.

In the accompanying drawings, Figure 1 represents in perspective an electro-plating apparatus embodying a preferred form of my invention.

Fig. 2 represents in front elevation my unitary agitating attachment removed from the tank.

Fig. 3 represents a guide bracket for the cathode, a pair of which are adapted to be applied either to the uprights or to the tank.

Similar numerals of reference indicate corresponding parts.

Referring to the drawings:

1 designates a typical plating tank for holding in solution the articles to be plated, which is composed of the bottom 2, the ends 3, and the sides 4, and which may be of any preferred dimensions and construction and material.

My unitary agitating attachment which I apply to any type of tank is shown detached in Fig. 2, and comprises the following component elements, namely:—5 are a pair of spaced uprights or supporting frames, preferably made of wood, and of a length, say, of 3 feet above the tank and of the same length downwardly along its sides, which are adapted to be secured by fastening devices, such as the bolts 6, to the ends of the tank.

Connecting these uprights together preferably in parallelism is a transverse, central rod 7, which is the cathode, and hereinafter termed the cathode rod, the ends of which pass through slots 8 in the uprights, and are provided with locking collars 7^a to prevent endwise movement relatively to the uprights under the regulations of the collar 7.

In the application and connection of the pair of uprights to and with a tank, a pair of guide brackets or metal ways or guides 10, shown in Fig. 3, are as a matter of preference used and adapted to be connected as to their bases 11, either with the tank ends or with the insides of the uprights.

12 are a series of connecting or eccentric rods, the lower ends of which are formed with collars 13 mounted on the cathode and effecting a loose connection provided with eccentric straps 14, which embrace eccentricities

15, fastened or formed upon the eccentric driving shafts 16, which shaft is journaled in bearings 17 at the upper and preferably the outside ends of the uprights 5, and serves 5 in connection with the cathode 7 to fasten together the uprights.

One end of the eccentric shaft 16 is locked against sidewise movement through its bearing 17 by an adjustable locking collar 18, 10 while the other end extends through its bearing 17, on the other upright, and is provided with similarly adjustable fast and loose pulleys 19 and 20, through the driving of which rotation is imparted to said 15 shaft, with the result that the operation of the eccentrics 15 through the connecting rods 12, will occasion a predetermined vertical reciprocatory movement of the negative cathode 7, through the slots 8 in the uprights 20 and the slots 9 in the guide brackets 10.

21 designates a pair of rods being the typical positive anodes of the apparatus, which, as in the usual practice, are mounted, conveniently by box-like fastenings 22 secured upon the ends 3 of the tank, so as to be in parallelism.

23 designates a rack or plurality of racks, for carrying the articles to be plated in submergence in the electrolyte, which may be of 30 any desired shape but are each preferably composed of transverse rods or wires 24, and one of vertical suspending rods 25 which extend upwardly and terminates in hooks 26, adapted to be hung over the cathode rod.

35 The electrical connections are not illustrated because they are of the usual kind and are well understood in the art.

Such being a preferred and very simple construction embodying my invention, its 40 operation will be easily understood.

Rotation of the eccentric driving shaft 16 through the driving pulleys 19 and 20, or other driving devices, will occasion the throw of the eccentrics 15, and accordingly 45 to the proportions of the eccentrics 15, impart through the connecting rods 12, a lift and drop of the cathode rod of the desired extent, with the result of the continuous and correspondent lifting and dropping of 50 the carrying racks and the carried articles to be plated.

By making the eccentric shaft and the cathode rod of any desired lengths, and making the locking collars 18 and 7^x move- 55 able lengthwise on them, I am enabled to adjust the uprights and the attachment as an entirety, to tanks of different lengths.

Although I do not limit myself to it, I prefer in practice to drive the eccentric 60 shaft at fifteen revolutions per minute with a driving stroke by one inch, and this because I find that the agitation of the work in the solution to the extent of a vertical movement of one inch prevents pitting, 65 drives off all the hydrogen and oxygen gases

from the work being plated, and keeps it smooth and bright.

Having thus described my invention I claim,—

1. An agitating mechanism for attachment to and removal from a plating tank, which comprises in combination the following instrumentalities, namely:—a pair of spaced uprights embodying longitudinal slots,—an eccentric driving shaft connecting 70 and rotatable with respect to said uprights,—means for rotating said shaft,—a cathode rod connecting and vertically reciprocable with respect to said uprights, and having its ends extending through the slots 75 thereof,—connecting rods eccentrically connected with said eccentric shaft and loosely connected with said cathode rod,—and means for connecting with and for suspending the cathode rod articles to be plated, the foregoing being attachable to or disconnected 80 from the plating tank as a unit.

2. In combination with a tank for containing plating fluid and with anodes applied to said tank,—an agitating mechanism for attachment to and removal from said tank, which comprises the following instrumentalities, namely:—a pair of spaced uprights having longitudinal slots intermediate of its end,—an eccentric driving 95 shaft connecting and rotatable with respect to said uprights,—means for rotating said shaft,—a cathode rod vertically reciprocable with respect to said uprights and having its ends guided in said slots,—connecting rods eccentrically connected with said eccentric shaft and loosely connected with said cathode rod,—and means connected with and for suspending from the cathode rod articles 100 to be plated, the foregoing being attachable 105 to or disconnected from the plating tank as a unit.

3. An agitating mechanism for attachment to and removal from a plating tank, which comprises in combination the following instrumentalities, namely:—a pair of spaced uprights having longitudinal slots,—an eccentric driving shaft connecting and rotatable with respect to said uprights, and provided with an adjustable locking collar,—means for rotating said shaft,—a cathode rod connecting and vertically reciprocable with respect to said uprights, and having its ends extending through the slots thereof and provided externally of said uprights with 110 locking collars,—connecting rods eccentrically connected with said eccentric shaft and loosely connected with said cathode rod,—and means connected with and for suspending from the cathode rod articles to be 115 plated.

4. In combination with a tank for containing plating fluid and with anodes applied to said tank,—an agitating mechanism for attachment to and removal from said 120

5 tank, which comprises the following instrumentalities, namely:—a pair of spaced uprights embodying longitudinal slots,—an eccentric driving shaft connecting and rotatable with respect to said uprights, and provided with an adjustable locking collar,—means for rotating said shaft,—a cathode rod connecting and vertically reciprocable with respect to said uprights and through 10 the slots thereof and provided externally of said uprights with locking collars,—connecting rods eccentrically connected with said eccentric shaft and loosely connected with said cathode rod,—and means connected 15 with and for suspending from the cathode rod articles to be plated.

20 5. An attachment to a plating tank, comprising a pair of uprights having guide slots therein intermediate of their ends, a cathode rod having its ends guided in said slots, guiding collars on the outer ends of said cathode rod, an eccentric driving shaft, having its ends mounted in the top of said uprights, eccentric rods having their lower ends 25 loosely attached to said cathode rod and their upper ends actuated by said shaft, means for driving said shaft, and means depending from said cathode rod for supporting and actuating the articles to be plated,

the foregoing being attachable to or disconnected from the plating tank as a unit. 30

6. The combination of a cathode rod, means for raising and lowering it, means for guiding the ends of said rod and a vertical rod 25 having transverse wires 24 and an upper hook 26, detachably connected to 35 said cathode rod.

7. An attachment to a plating tank comprising a pair of uprights having guide slots therein intermediate of their ends, a cathode 40 rod having its ends guided in said slots, guiding devices on the outer ends of said cathode rod, an eccentric driving shaft having its ends mounted in the top of said uprights, eccentric rods having their lower 45 ends loosely attached to said cathode rod and their upper ends actuated by said shaft, means for driving said shaft, and a vertical rod 25 having transverse wires 24 and an upper hook 26 detachably connected to said 50 cathode rod, the forgoing being attachable to or disconnected from the plating tank as a unit.
